DESIGN FOR WALL-PAPER.

Design No. 13,149, dated August 8, 1882.

UNITED STATES PATENT OFFICE.

EDUARD LEISSNER, OF NEW YORK, N. Y.

DESIGN FOR WALL-PAPER.

SPECIFICATION forming part of Design No. 13,149, dated August 8, 1882.

Application filed June 30, 1882. Term of patent 3½ years.

To all whom it may concern:

Be it known that I, EDUARD LEISSNER, of New York, in the county and State of New York, have invented a new and original Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

R represents a band containing vase-shaped figures a, of different heights, set in pairs of the same height, and alternating with figures b resembling tassels. These figures a and b are set upon a band composed of rectangular figures, which contain small circular figures. The figure L is circular, with a star-shaped center. The figure M consists of a series of overlapping wings surrounding a circular center. The figure O resembles a flower of geometrical pattern. The figure P has a center somewhat resembling a four-leaved clover surrounded by

half-circles. C is a band containing a block pattern broken by circles at intervals. The interstices between the figures are occupied by what resembles an open mesh or net-work, which seems to unite the various figures. 30

K designates the whole stripe, made up of the various figures.

I claim—

1. The design for wall-paper, consisting of the band R, containing figures a and b, substantially as shown. 25
2. The design for wall-paper, consisting of the figures L M O P, substantially as shown.
3. The design for wall-paper, consisting of the band R and figures L M O P, substantially 40 as shown.
4. The design for wall-paper, consisting of the band C, substantially as shown.
5. The design for wall-paper, consisting of the stripe K, containing figures a, b, L, M, O, 45 P, and C, substantially as shown.

EDUARD LEISSNER.
